Aubrey W. Epps, Jr., and Felix C. Winn, Jr.,
Sanford, Fla.

Application May 27, 1959, Serial No. 56,099

Term of patent 14 years

(Cl. D56—4)

FIG. 1

FIG. 2

Fig. 1 is a perspective view of a television receiver with boom supported picture unit, showing our new design; and

Fig. 2 is another perspective view thereof.

The side not visible is the same as the visible side and the back is plain and unornamented.

The broken line showing of a mounting means in Fig. 2 is for illustrative purpose only.

We claim:

The ornamental design for a television receiver with boom supported picture unit, as shown and described.
